UNITED STATES PATENT OFFICE

160,086

COMBINED KNIFE AND KITCHEN UTENSIL RACK

Ernest J. Hubbert, Kansas City, Mo.

Application November 28, 1949, Serial No. 6,305

Term of patent 14 years

(Cl. D44—29)

To all whom it may concern:

Be it known that I, Ernest J. Hubbert, a citizen of the United States of America and a resident of Kansas City, Jackson County, State of Missouri, have invented a new, original, and ornamental Design for a Combined Knife and Kitchen Utensil Rack, of which the following is a specification, reference being had to the accompanying drawing, forming a part thereof.

In the drawing, the figure is a perspective view of the combined knife and kitchen utensil rack, showing my new design.

I claim:

The ornamental design for a combined knife and kitchen utensil rack, substantially as shown.

ERNEST J. HUBBERT.
